UNITED STATES PATENT OFFICE.

STEPHEN D. TUCKER, OF NEW YORK, N. Y.

WEB-PRINTING AND DELIVERY APPARATUS.

SPECIFICATION forming part of Letters Patent No. 372,721, dated November 8, 1887.

Application filed June 22, 1883. Serial No. 98,961. (No model.)

To all whom it may concern:

Be it known that I, STEPHEN D. TUCKER, a citizen of the United States, residing in the city of New York, county of New York, and 5 State of New York, have invented certain new and useful Improvements in Web-Printing and Delivery Apparatus, fully described and represented in the following specification and the accompanying drawings, forming a part of the 10 same.

This invention relates to that class of web-perfected printing-machines in which the forms for printing both sides of the web are carried upon a single cylinder, and in which the 15 web after being printed upon one side is turned over and re-presented to the same form to be printed upon its opposite side, the travel of the web between the printing of its opposite sides being so distanced that the inside pages 20 of the sheets upon one side will fall opposite the outside pages of the sheets upon the other, and vice versa.

The machines of this class possess many desirable characteristics and have gone into very 25 extensive use, particularly in those establishments where it is desired to print directly from the type instead of from stereotype or other plates. When, however, the printing is to be done directly from the type, it is necessary 30 to make the form-cylinder of a very much larger size than when plates are to be used, as in practice it is found impossible to successfully secure ordinary parallel type onto a cylinder as small as those commonly employed when plates are used. When a cylinder 35 of sufficient size to successfully carry the forms in type is used, it is found so large that the forms for printing both sides of an ordinary folio or four-page newspaper will occupy 40 very much less than its whole circumference, and this fact makes it necessary in this class of machines, when the printing is to be done directly from the type, to provide register-rolls and an increased number of impression-45 cylinders, so that the forms will make two or more impressions upon each side of the web at each revolution of the form cylinder.

It will readily be seen that when a web is perfected by a mechanism of this character 50 its alternate sheets or series of sheets will have different matter upon their upper or outer surfaces, and if the columns of the forms are placed

lengthwise of the cylinder, as is usual when printing from type, the heads of their pages will be at opposite sides of the machine, and 55 these facts make it necessary, if the sheets are to be folded, to provide two mechanisms for that purpose which will operate to fold alternate sheets or series of sheets in opposite directions, so as to bring the same page or pages 60 upon the outside of all the sheets after they are folded.

One branch of the present invention relates especially to a folding delivery apparatus 65 adapted to co-operate with a printing mechanism which prints a web in the manner above specified; and it consists in various details of construction and combinations of parts, hereinafter fully explained, by which the sheets are folded and delivered in a uniform condition. 70

There are at the present time many newspaper establishments which desire to issue at different times papers of varying sizes—such, for example, as papers of four, eight, or twelve 75 pages. To fully meet the wants of such establishments it is necessary not only to produce a printing mechanism which is rapid and reliable in its operation, but to provide means by which such mechanism can be readily capacitated to produce either of the products desired. 80

Another branch of the invention relates more particularly to the printing mechanism; and it consists of means by which this mechanism can 85 be operated at will to produce papers of various sizes.

In the accompanying drawings, Figure 1 is a side elevation of a printing mechanism of the character specified, provided with means 90 by which it is capacitated to produce papers of different sizes. Fig. 2 is a longitudinal vertical section of the same. Fig. 3 is a side elevation of the delivery apparatus. Fig. 4 is a plan view of the mechanism shown in Fig. 3. 95 Fig. 5 is an end elevation of the delivery apparatus. Fig. 6 is a transverse vertical section of the same. Figs. 7 and 8 are diagrammatic sections illustrating the operation of the delivery apparatus. Fig. 9 is a plan view of 100 the web-turner, by which the web is reversed after being printed upon one side, so as to present its unprinted side to the forms. Fig. 10 is a cross-section of the same. Figs. 11 and 12

are like views showing the same turner adjusted to a different position. Figs. 13 and 14 are plan views showing different means for adjusting the turner. Fig. 15 is a plan view 5 of the delivery mechanism when operating to deliver four-page papers. Fig. 16 is a plan view of a web associating and pasting apparatus for producing a twelve-page paper. Fig. 17 is a longitudinal vertical section of the same. Fig. 18 is a side elevation of the delivery mechanism, showing the folding-cylinders arranged parallel with instead of at right angles to the printing-cylinders. Fig. 19 is a longitudinal vertical section of the same. Fig. 20 is an end 10 elevation of the same. Fig. 21 is a plan view 15 of the web-associating apparatus of Figs. 18, 19, and 20. Fig. 22 is a longitudinal vertical section of the pasting and registering devices. Fig. 23 is a detail to be hereinafter referred 20 to. Figs. 24, 25, and 26 are diagrams showing, respectively, the order of the impressions upon the web when four, eight, and twelve 25 page papers are produced.

Referring to Figs. 1 to 4, it will be seen that 25 the printing mechanism shown in the present case is, as to its general construction, the same as that shown in United States Letters Patent No. 274,584, consisting, essentially, of a form-cylinder, four impression-cylinders, two register-rolls, a web-turner, and suitable inking 30 mechanism.

The form-cylinder 100, which is of the usual construction and of a size sufficient to permit ordinary parallel type to be fastened to its periphery, is mounted in bearings in an appropriate frame-work, and is provided with means for carrying eight forms of type, which, for convenience, it will be assumed are of a suitable size to print the pages of an ordinary 40 eight-page newspaper. These forms are arranged in two groups located diametrically opposite each other upon the cylinder, each group consisting of two pairs placed end to end with relation to the length of the cylinder, 45 and each pair occupying one-fourth of its circumference. These forms, it will be assumed, are placed upon the cylinder so that the columns of matter will, as is usual when printing from type, lie lengthwise of the cylinder, the 50 heads of the columns of the groups upon the opposite sides of the cylinder pointing in opposite directions and so arranged that those for printing pages 6 3 and 8 1 will form one group with their heads pointing to the front 55 of the machine, those for printing pages 7 2 and 5 4 the other group, with their heads to the rear, the forms for pages 6 8 and 7 5 being the advance ones of their respective groups as the cylinder revolves.

60 The spaces upon the cylinder between the groups of forms are occupied by ink-distributing tables or surfaces 101, which are supplied with ink in the usual manner, and from which the ink is taken and supplied to the 65 forms by ordinary form-rollers, 102, operating in the same manner as in the well-known Hoe type-revolving press.

Inasmuch as the forms cover only one-half the circumference of the form-cylinder, it becomes necessary, as hereinbefore set forth, in 70 order to print the whole surface of the web, that each form should act twice upon each side of the web at each revolution of the cylinder. To accomplish this four impression-cylinders, 75 103 104 105 106, and two register-rolls, 107 108, are provided. The web to be printed is led from a roll, 109, around a leading-roll, 110, and thence to and around the first impression-cylinder, 103. After passing this cylinder it is led outward around the register- 80 roll 107, and thence inward to and around the second impression-cylinder, 104. The register-roll 107 is placed at such a distance from the impression-cylinders 103 104 that the advance edge of the impression on the web given 85 by the first group of forms against the cylinder 103 will arrive upon the cylinder 104 just in time to exactly join with the rear edge of the impression given by the same group of forms against that cylinder. From this it results that the first group of forms makes two 90 impressions upon the web in succession, the second impression being just in advance of the first.

Following the rear edge of the impression 95 made by the first group of forms against the cylinder 103 will be a blank space equal to the space upon the form-cylinder between the groups of forms. At the end of this space the second group of forms will make an impression 100 upon the web against the cylinder 103, and passing to the cylinder 104 will make a second impression just in advance of the first, which second impression will just join the impression given by the first group of forms upon 105 the cylinder 103, and thus fill the blank space referred to. This operation being repeated at each revolution of the form-cylinder, one side of the web will be wholly covered, the pages for each side of the sheet occurring 110 twice in succession, as $\frac{1}{6} \frac{1}{3}$, $\frac{1}{6} \frac{1}{3}$, $\frac{5}{6} \frac{4}{3}$, $\frac{5}{6} \frac{4}{3}$, &c., as shown in Fig. 25. After passing the impression-cylinder 104 the web, now printed upon one side, is conducted around a leading-roll, 111, thence around a web-turner, by 115 which it is reversed, so as to present its unprinted side to the forms, and thence around the leading-rolls 112 113 to and around the impression-cylinder 105. From this cylinder the web passes outward around the register-roll 108, and thence inward to and around the last impression-cylinder, 106. The operation of the form-cylinder in connection with the impression-cylinders 105 106 to print the side of the web now presented is exactly the same 120 as already described in connection with the cylinders 103 104.

The distance traveled by the web between the cylinders 104 105 will be so regulated by the position of the rolls 111 112 113, one or 130 more of which may be adjustable, that the impressions upon the opposite sides of the web will be in perfect register, and that the pages for the insides of the sheets will be backed by

the pages for the outsides of the sheets, and vice versa.

The printing mechanism just described may be provided with tapes, as 114, arranged as shown and described in my application for Letters Patent filed in the United States Patent Office April 27, 1882, Serial No. 59,747, and it will also be provided with forwarding-rolls, as 115, operating in connection with the register-rolls in the manner set forth in the Letters Patent hereinbefore referred to.

Motion is communicated to the above-described mechanism by the driving shaft 117 through the gear 116, fixed thereon, and which engages with the gear 170 on the form-cylinder shaft, this gear in turn driving the impression-cylinders 103 104 105 106 through their respective gears 171 172 173 174, as shown in Figs. 1 and 2.

20 The forms, as before stated, are so placed upon the cylinder 100 that those for printing one side of the sheets will be headed in one direction and those for the other side of the sheets in the opposite direction, so that the heads of the pages in register upon the opposite sides of the web will point in the same direction, and whereby, also, two succeeding sheets will have their heads toward one side of the machine and the next two toward the opposite side of the machine, as shown in Figs. 24, 25, and 26. After leaving the last impression-cylinder the printed web passes beneath a roll, 118, when it is split upon the line *xx* (see Fig. 25) by a slitter, 119, so as to pass forward in two sections. From the roll 118 the two sections of the web are led around turning-bars 120 121, so arranged, as shown in Fig. 4, that the sections are turned at right angles to their previous path of travel and brought directly 40 one above the other. The sections thus associated then pass beneath the roll 122 and between the cutting-cylinders 123 124, by which they are partially severed upon the lines *zz*.

In order to secure the proper register between the sheets of the two sections of the web after they are associated by passing around the bars 120 121, the section which passes around the bar 121 is, after being split from its companion, caused to take a longer 50 path of travel before reaching its turning-bar. This is effected by means of register-rolls, as 125 126 127, arranged as shown in Figs. 3 and 4, the section passing beneath roll 125, upward around roll 126, and thence returning beneath roll 127. The roll 126 may be made adjustable, as shown, so as to vary the distance traveled by this section of the web as may be desired.

If it is desired to unite the two sheets which 60 go to make up the complete product, it may be done by means of a paster, 128, arranged, as shown in Fig. 3, to apply lines of paste at the proper points as the section of the web passes around the roll 127.

65 The cutting-cylinders 123 124, which are of the same size as the impression-cylinders, are connected by gears 175 176, and made to run

in unison therewith by means of the train of gears 177 178 179 180, bevel-gears 181 182, and gears 183 184, the gear 184 being of double 70 width, so as to engage with both the gears 183 176. The gear 177 drives the roll 118, while the gear 178, through the gear 186, drives the registering-roll 108. The gear 180 is fixed on the shaft 187, carrying the revolving pasting-blade, and drives the register-roll 127 and paste-fountain roll 188 through their respective gears 189 190. The bevel and spur gears 182 183 are secured together and run loose on a stud, 191.

80 The associated sections of the web, after being partially severed by the cutting-cylinders 123 124, pass into the bite of the series of accelerated tapes 2 3, which complete the severance of the sheets from the web and deliver 85 them to the folding mechanism. This mechanism consists, primarily, of the folding-cylinders 129 130, mounted side by side and slightly separated, and which, as here shown, are arranged to give two parallel folds to the 90 sheets. These cylinders are driven turn for turn with the cutting-cylinders by the gear 184 through the train of gears 185 192 193, the latter being fixed to the shaft of the cylinder 130. These cylinders are of slightly greater diameter than the cutting-cylinders, and are connected, so as to run in unison, by the gears 194 195, and these gears also drive the two series of tape-pulleys 16 17 through their respective gears 196 197, and thus give to the two series 100 of tapes 2 3, that serve to convey the sheets from the cutting to the folding cylinders, a slightly accelerated speed. The series of tapes 2 pass around pulleys 14, thence around pulleys 21, thence around pulleys 16, and above 105 pulleys 18, returning around pulleys 20. The series 3 pass around pulleys 15, thence around pulleys 21, thence between pulleys 16 and 17, returning over pulleys 19.

110 It will readily be understood that in folding newspapers it is very desirable, no matter how many folds are made in the sheet, that the title or heading on the first page should always be left in sight. It is obvious, therefore, from an inspection of Fig. 25, which represents the 115 web as it issues from the printing-machine, that to accomplish this two succeeding pairs of sheets must be folded in one direction and the next two pairs in the opposite direction. To effect this the sheets, as they emerge from 120 between the pulleys 16 17, pass into the control of an oscillating guide, 22, which is operated so as to direct two successive sheets alternately to each of the pair of folding-cylinders 129 130, which cylinders are so operated 125 as to fold their respective sheets in opposite directions.

The oscillation of the guide 22 is effected by means of an arm, 23, secured to the outer end of the shaft upon which said guide is mounted 130 and to which is attached a rod, 24, (see Fig. 6,) carrying a stud, 25, which lies in the groove of a cam, 26, secured to a gear, 27, which engages with a gear, 28, of one-fourth

its size, mounted upon the shaft of the cylinder 129. The groove of the cam 26 is of such shape that the guide 22 will be caused to swing from one cylinder to the other at each second revolution and will remain in each position to which it is swung while the cylinders make two revolutions.

The cylinders 129 130 are each provided with a pair of co-operating folding-rolls, as 29 30, a rotating folding-blade, as 31 32, and two sets of sheet-grippers, as 33 34 35 36, all of which are of the usual construction and operated in the usual manner to take the sheets and fold them from the cylinders. These cylinders are also each provided with two series of co-operating tapes, 4 5 and 6 7, the purpose of which is to return the once-folded sheets to the cylinders to receive a second fold. The tapes 4 pass around the outer one of the folding-rolls, 29, thence outward around pulleys 37, thence inward around pulleys 38, returning around pulleys 39. The companion series 5 pass around the pulleys 40, located just beneath the roll 29, thence around pulleys 37, thence above pulleys 38 and around pulleys 18, returning around pulleys 41. The tapes 6 pass in like manner around the outer one of the folding-rolls, 30, thence outward around pulleys 42, thence inward around pulleys 43, returning around pulleys 44. The companion series 7 pass around the pulleys 45, located just beneath the roll 30, thence around pulleys 42, thence above pulleys 43 and around pulleys 19, returning around pulleys 46.

The exits from between the folding-rolls 29 30 are controlled by a pair of oscillating switches, 48 49, which are operated so as to direct the sheets from between said rolls into the bite of the tapes 4 5 and 6 7 or along the converging sides of the stationary guide 47 into the bite of the rolls or pulleys 51 52. The pulleys 51 52 are each provided with two series of co-operating tapes, 8 9 and 10 11. The series 8 pass around the pulleys 51, thence between the pulleys 53 55, thence outward above a pair of folding-rolls, 66, returning around the pulleys 59 57. The companion series 9 pass between pulleys 53 55, and thence outward above the folding-rolls 66, returning around the pulleys 61. The series 10 pass around the pulleys 52, thence between the pulleys 54 56, thence outward above a pair of folding-rolls, 67, thence around pulleys 60, upward and around pulleys 64, and downward around pulleys 65, returning around pulleys 58. The companion series 11 pass between the pulleys 54 56, and thence outward above the folding-rolls 67, returning around the pulleys 62.

The series of tapes 10 are provided with a series of short co-operating tapes, 1, which pass around the pulleys 63 64, as shown in Figs. 5 and 6, and thus, with the switch 90, form a sheet-collecting device for delivering two sheets together, as will hereinafter appear.

The oscillation of the switches 48 49 is ef-

fected by means of rock-arms secured to the shafts upon which said switches are mounted and connected by rods 68 69 with one of the arms of a pair of bell-crank levers, the opposite arms of which are provided with studs which are acted upon by a grooved cam, 70, secured to the gear 71, which gear makes but one revolution to four revolutions of the folding-cylinders. The oscillation of the switch 50 is effected in a similar manner through a rod, 72, provided with a stud which is acted upon by a grooved cam, 73, secured to the same gear.

The folding-rolls 66 are provided with an ordinary vibrating folding-blade, 74, which operates to fold the sheets between said rolls as they are brought to rest in proper position against the stops 88. As the sheets emerge from the rolls 66 they pass beneath the guides 82 (see Fig. 3) into position above a second pair of folding-rolls, 76, between which they will be folded by a second vibrating blade, 78, after which they will be taken by the fly 80 and deposited upon the piling-table 84.

The folding-rolls 67, like the rolls 66, are provided with a vibrating blade 75 and stops 89. These rolls are also provided with a pair of co-operating folding-rolls and blade, 77 79, similar to the rolls and blade 76 78, and also with guides 83, a fly, 81, and a piling-table, 85, similar to those just described.

The various parts of the delivery mechanism receive motion through suitable gearing connecting them with each other and with the cutting and folding cylinders, said gearing being so proportioned as to properly time said parts with relation to each other and to the printing mechanism, all in the manner well understood by those familiar with the art, and consequently requiring no specific description.

The operation of the delivery apparatus is as follows: Let it be supposed that the web printed in the order shown in Fig. 25 has been split and its sections associated in the manner shown in Fig. 4, and that the first pair of associated sheets which emerge from the guides 22 have pages 8 1 next to the cylinder 130, with the heads of the columns at the front of the machine with reference to Figs. 5 and 6. At this time the guide 22 will be in the position shown in Fig. 6, so that as the leading ends of this pair of sheets arrive at the proper point they will be taken by the grippers 33 and carried around upon the cylinder 129, from which they will, at the proper time, be folded by the blade 31 between the rolls 29. (See Fig. 6.) The switch 48 will at this time be in such position that this pair of sheets, instead of passing directly to the pulleys 51 52, will be guided into the bite of the tapes 4 5. The second pair of sheets, which, like the first, have the pages 8 1 next to the cylinder 130 and the heads of their columns at the front of the machine, will be taken by the same grippers and folded in the same manner as shown in Fig. 7. As the third pair of sheets, which will have the pages 8 1 next to the cylinder 129 and the heads of their columns at the

rear of the machine, emerge from the guide 22, said guide will be shifted to the position shown in Figs. 7 and 8, so that this pair will be taken by the grippers 35 and carried 5 around upon the cylinder 130, and at the same time the first pair of sheets, which have been carried forward between the tapes 4 5, will be re-presented to the cylinder 129 in such position as to be taken by the grippers 10 34, as shown in Fig. 7. After the second pair of sheets have passed from the rolls 29 the switches 48 49 will be shifted to the position shown in Fig. 8, so that the third pair of sheets, when folded by the blade 32 between the rolls 15 30, will pass into the bite of the tapes 6 7, while the first pair of sheets, which will at the same time be folded a second time between the rolls 29 by the blade 31, will pass directly to the pulleys 51 52, as shown in Fig. 8. The 20 fourth pair of sheets, which, like the third, have their pages 8 1 next to the cylinder 129 and the heads of their columns at the rear of the machine, will be taken by the grippers 35 and folded by the blade 32 in the same manner, and at the same time the second pair will 25 be taken by the grippers 34 and receive their second fold between the rolls 29. After this the guide 22 and the switches 48 49 will be again shifted, and the operation will be reversed, the fifth and sixth pairs of sheets being taken by the cylinder 129 and given their first fold while the third and fourth pairs are receiving their second fold from the cylinder 30 130. As the first and second pairs of sheets 35 pass between the pulleys 51 52, the switch 50 will be in the position shown in Fig. 8, so that said sheets will be guided into the bite of the tapes 8 9 and brought to rest in succession above the rolls 66, between which they 40 will be folded by the blade 74, thus receiving a third fold at right angles to the first two, after which they will pass beneath the guides 82 into position above the rolls 76. (See Fig. 45 3.) From this position they will be folded between the rolls 76 by the blade 78, thus receiving a fourth fold parallel to the third, after which they will pass to the fly 80 and be piled upon the table 84. After the first and second pairs of sheets have passed the pulleys 51 52 50 the switch 50 will be shifted to the position shown in Fig. 7, so as to direct the third and fourth pairs into the bite of the tapes 10 11, and these pairs will in like manner pass to the rolls 67 and be folded by the blade 75, after 55 which they will pass beneath the guides 83, be folded between the rolls 77 by the blade 79, and piled upon the table 85 by the fly 81. After the third and fourth pairs of sheets have passed the pulleys 51 52 the switch 50 will be 60 again shifted, and so the operation will be repeated.

It has already been stated that the pages 8 1 of the first and second pairs of sheets are, as they enter the folding mechanism, next to the 65 cylinder 130, with the heads of their columns at the front of the machine, while the corresponding pages of the second and third pairs

are next to the cylinder 129, with the heads of their columns at the rear of the machine, page 8 in each case being upon the advance and 70 page 1 upon the rear portion of the sheet. From this it results that after the first fold has been made the sheets pass into the bite of the tapes 4 5 and 6 7, with page 1 next to the tapes 5 and 7, and that after the second fold has 75 been made they pass into the bite of the tapes 8 9 and 10 11, with the right-hand portion of page 1 next to the tapes 9 and 11, and consequently next to the folding-rolls 66 and 67. After the third fold is made the sheets pass 80 from the folding-rolls in opposite directions, those from the rolls 66 passing to the left, as shown in Fig. 3, and those from the rolls 67 to the right, so that in each case the upper right-hand portion of page 1 is brought next to the 85 final folding-rolls, thereby leaving that portion of the heading exposed after the fourth or final fold is made.

It frequently happens that it is desirable to deliver different portions of the same issue of 90 a newspaper in different forms—as, for example, one part folded to a form suitable for mailing and the other part folded to a form suitable for the carrier. This can be accomplished in the mechanism shown in the present case by removing the stops 89 and throwing the folding-blade 75 out of operation. Two succeeding sheets will then pass to the folding-rolls 66 67 and be delivered to the fly 80 after receiving four folds, while the next two 100 sheets, instead of being folded between the roll 67, will pass by said rolls and the first one of the two will be guided up between the pulleys 60 63 by the vibrating switch 90 (see Fig. 6) into the bite of the tapes 10 11, by which it 105 will be carried up over the pulleys 64 and downward past the pulleys 63 into the bite of the rolls 62 65. In the meantime the switch 90, which is operated through a rod, 198, by a suitably-shaped cam fixed to the gear 71, will 110 have been rocked to its uppermost position, so that the second sheet will be guided directly between the rolls 62 65, when it will meet the first sheet and the two will issue together to the fly 86 and be laid upon the table 115 87, the speed of the fly being thus reduced one-half. If desired, all the sheets may be delivered in this form by simply fixing the switch 50 in the position shown in Fig. 6.

If at any time it is desired to produce a 120 product of one-half the volume of that just described, or, in other words, a product consisting of a single sheet instead of two sheets associated together, the forms will be removed from one end of the form-cylinder, 125 and a half instead of a full width web will be used. This narrow web, after being printed in the order shown in Fig. 24, will, as shown in Fig. 15, be led between the cutting-cylinders, when it will be severed upon the line *z z*. 130 The single sheets will then pass to the folding mechanism and be operated upon in precisely the manner already set forth in connection with pairs of sheets. If it should be desired

to construct a mechanism of this character which will be capacitated to produce a product consisting of three sheets associated and folded as just described, as well as a product 5 consisting of one or two sheets, the form-cylinder will be made of sufficient length to carry three forms abreast, and a web of a correspondingly increased width will be used. An extra slitter 119 will be provided, so that the 10 web may be split into three sections. An extra turning-bar 131 will also be provided, so that the three sections may be associated, and an extra register-roll 132, so that the pages upon the several sections may be brought into 15 proper register. The forms will be arranged upon the form-cylinder so as to print the web in the order shown in Fig. 26, after which the web will be split upon the lines $\alpha\alpha$, and its sections will be associated in the manner shown 20 in Figs. 16 and 17. The three-ply web thus formed will be severed upon the lines $\gamma\gamma$, and the three associated sheets will be folded and delivered in the manner set forth.

In a mechanism thus constructed a product 25 consisting of single sheets or of two associated sheets can be produced by omitting two-thirds or one-third of the forms and using a web of a correspondingly-reduced width.

It has already been explained how by varying 30 the width of the web printed upon a printing and delivering mechanism of the character herein shown can be operated to produce and deliver a product consisting either of single sheets or of two or more sheets associated together.

When a web of the maximum width is used, the forms will occupy the whole length of the form-cylinder; but when a web of one-half such width or of one-third or two-thirds such 40 width, according as the machine is a double or triple width one, is used the forms will occupy but one-half or one-third or two-thirds of the length of the cylinder. When both sides of the web are printed from the same cylinder, it 45 is necessary that the web should be turned between the printing of its opposite sides, so as to present the unprinted side to the forms, and when, as in machines of the class herein shown, both sides of the web are reprinted from the 50 same forms it is further necessary that this turning of the web should be effected without lateral transfer. It will readily be seen, however, that in order to secure this result—viz., the turning of the web without lateral transfer—it 55 is necessary that the point at which the bars of the turner cross each other should coincide very nearly with the center of the web. This might be effected by placing the forms in the center of the length of the form-cylinder; but this 60 would entail several serious inconveniences, such as printing on the impression-cylinders, where the center margins of the eight-page forms have left the blankets higher, the shifting of the turning-bars 119 or 120 to suit the 65 new position of the web, while also the distance of travel of the web from the press to the cutting and folding cylinders would be

changed and require readjusting, besides necessitating changes in other details, all of which would entail loss of time, liability of error, 7c and waste of paper. It is therefore highly desirable to place the forms at one end of the form-cylinder, which necessitates the placing of the web at the same side to correspond. From this it results that when a web of one-half or two-thirds width is used and is printed at one side of the machine it will pass to the turning apparatus in such position that its center does not coincide with the point at which the bars of the turner cross each other, and 80 consequently will be transferred laterally in being turned if the bars are in the same position as when operating upon a web of full width, so that its second side will be presented to the opposite end of the form-cylinder from 85 that upon which the forms are located. To obviate this difficulty the turning apparatus is arranged as shown in Figs. 9 and 10. This apparatus as here shown consists of two turning-bars, 147 148, arranged angularly across 90 the path of the web and at right angles to each other, and a leading-roll, 149, arranged at the ends of the bars and parallel to the path of travel of the web. The operation of this web-turning apparatus is well understood by those 95 familiar with the art, and consequently needs no specific description. The bars 147 148 and roll 149, instead of being attached to the frame of the machine, are mounted upon a carriage, 151, arranged to slide upon ways 152, and provided with a screw or other adjusting device, 150, by which its position can be changed so as to cause the point at which the bars 147 148 cross each other to coincide with the center of the web, no matter what its width. 105

In Figs. 9 and 10 the carriage 151 is shown adjusted to the proper position to cause the point at which the bars 147 148 cross each other to coincide with the center of a full-width web.

Figs. 11 and 12 show the turner adjusted to suit the half-width web, the forms and web in this case being placed to the rear side of the machine.

As the distance from the point of intersection of the turning-bars 147 148 to the roll 149 has not been changed in adjusting the turner, it follows that the length of web in the turner from the roll 111 to the roll 112 is the same as before, and consequently the pages to be 115 printed on its second side will register with those already printed on its first side, and if the forms for printing pages 1 4 are placed on the form of the cylinder in the position previously occupied by the forms for printing the pages 120 1 8 the web will issue to the folding mechanism, as shown in Figs. 15 and 24, and be 125 correctly folded without any adjusting of the cutting or folding mechanisms.

In Figs. 13 and 14 different means are shown 130 of adjusting the turner to suit the position of the half-width web. This is effected in Fig. 13 by shifting the positions of the bar 147 and of the roll 149. For this purpose the ends

of the bar are provided with bearings 153, which slide upon guides 154, and in which work screw-rod 156, which are connected together by bevel-gears 157, so as to be simultaneously 5 operated by the rod 158 and crank 159. The roll 149 is also mounted in sliding bearings 160, provided with nuts 161, in which work screws formed on an extension of the rod 158, and a rod, 162, which is connected to the rod 10 156 by bevel-gears 163. When the parts are thus arranged, by turning the crank 157 the bar 148 may be so adjusted as to cause the point at which it crosses the bar 147 to coincide very nearly with the center of the web, 15 whether the same be of full or one-half width, and the roll 149 will at the same time be so shifted as to preserve the proper distance from the point of intersection of the bars, and of course of the length of travel of the web.

20 In Fig. 14 substantially the same organization is shown, except that both the bars 147 148 are provided with sliding bearings and nuts, which are engaged by right and left hand screws on the rods 156, so that both bars are 25 moved to and from each other in effecting the adjustment. In this case both of the screws for moving the roll 149 are on independent rods 162, which are connected to the rod 156 by bevel-gears 163.

30 In a triple-width machine a product consisting of two associated sheets can be produced by omitting a set of forms at one end of the form-cylinder and using a web of proper width placed to correspond with the position 35 of the forms and shifting the position of the web-turner to properly reverse the web, while to produce a product consisting of single sheets upon a triple-width machine a single set of forms only will be used in the center of 40 the length of the form-cylinder, and a web of proper width will be placed in a central position and the web turner will occupy the same central position as when reversing the full-width web.

45 In adjusting the turning apparatus in either of the ways shown the tape 114 will automatically change its position, so that whatever the width of the web the tape will always remain at the same distance from its edges.

50 It will be apparent that other forms of web turning or reversing apparatus—such, for example, as those shown in Figs. 7 and 9 of United States Letters Patent No. 212,880—may be used instead of that herein shown and made 55 adjustable in the same manner.

In Figs. 18 to 23 an organization is shown in which the folding-cylinders 129 130, instead of being placed at right angles to the printing-cylinders, are placed parallel thereto. 60 When the folding-cylinders are arranged in this manner, instead of each section of the web being led around one turning-bar, one section will be transferred laterally by being led around both bars, so that the two sections 65 will be associated without changing their direction of travel, as shown in Fig. 21. In this case the register-rolls 125 126 127 and the

pasting apparatus will be arranged as shown in Figs. 19 and 22.

The mechanism for the subsequent manipulation of the web and sheets may be exactly the same as already described, or it may be modified, as shown in Figs. 18, 19, and 20. In the organization shown in these figures the cutting-cylinders 123 124 and accelerated 70 tapes 2 3 are omitted, the web being led directly to the folding-cylinders, which, instead of being provided with grippers, are provided with impaling-pins 133 134 and with a severing-blade, 135, and co-operating groove 136. 80 The severing of the web being accomplished by the folding-cylinders, the vibrating guide 22 becomes unnecessary, and is therefore also omitted, the mechanism for operating the pins being so arranged that alternate pairs of 85 sheets will be taken by each cylinder. In this organization, also, the switches 48 49 and the tapes 4 5 and 6 7 are omitted, so that the cylinders 129 130 are capacitated to impart but a single fold to the sheets. The tapes 8 are 90 arranged to pass from the pulleys 57 around the outer one of the rolls 29, and thence directly to the pulleys 55, and return above the folding-rolls 66 around the pulleys 59, while the companion-tapes 9 are arranged to pass 95 from the pulleys 53 around the inner one of said rolls 29, thence to the pulleys 55, and return around the pulleys 61. The arrangement of the tapes 10 11 is correspondingly modified.

The operation of the cylinders 129 130 in 100 imparting the first fold to the pairs of sheets is the same as already described, after which the sheets pass into the bite of the tapes 8 9 and 10 11, and are conducted directly to the folding-rolls 66 67 in the order already set 105 forth. The sheets presented to the rolls 66 67 will be folded between said rolls by the blades 74 75, after which they will enter the bite of the tapes 12 13, and these tapes will convey the sheets from the rolls 67 downward and 110 outward to the right, and then around the roll 92 inward to the rolls 77, as shown in Fig. 20, while the sheets from the rolls 66 will be conveyed downward and outward to the left, and thence inward to the roll 76, thus bringing the sheets into proper positions to have 115 their headings folded outside. The rolls 76 77 in this case are set at right angles to the rolls 66 67, so that the third fold imparted to the sheets is at right angles to the second. The 120 tapes 12 pass around pulleys 90, (see Figs. 20 and 23,) thence outward around pulleys 92, thence inward above the rolls 76 77, returning 125 around pulleys 93. The companion series pass around the outer one of the rolls 66 67, thence outward around pulleys 92, thence 130 across the machine and around the pulleys 94, thence backward, returning around pulleys 95. As the sheets arrive in position above the rolls 76 77, they will be folded between 135 said rolls by the blades 78 79, thus receiving their third fold, after which they will pass into the bite of the tapes 139 140, which pass, respectively, around the inner one of said fold-

ing-rolls and pulleys 141 and the outer one of said rolls and pulleys 142, by which they will be conveyed to the single fly 137, to be piled upon the table 138.

5 If it is desired in this organization to deliver the sheets with two instead of three folds, the switches 145 will be shifted from the position shown in Figs. 20, 23; for which purpose handles, as 146, may be provided, so that the sheets as they emerge from the rolls 66 67, instead of entering between the tapes 12 13, will be guided into the bite of the tapes 98 99 and delivered from between the pulleys 96 97, whence they will be taken by the flies 143 and piled upon the tables 144.

If it should be desired to deliver a part of the sheets in one form and the remainder in another, the switches 145 may be so arranged, that the sheets from one pair of folding-rolls 20 will be guided into the tapes 12 13, and those from the other into the tapes 98 99, thereby delivering one half the sheets to the fly 137 with three folds and the other half to one of the flies 143 with two folds.

25 It will be apparent that single sheets, as well as sheets associated in pairs, may be operated upon by this organization the same as by the organization first described, and also that three, or more sheets may, if desired, be associated 30 and delivered in the same manner.

It is also apparent that the delivery apparatus thus organized may be located in the same position with relation to the printing-cylinders as that first described, or that the 35 organization first described may, if preferred, be so located that its folding-cylinders will be parallel with the printing-cylinders.

The threading-tapes 114 are not herein claimed, as they are claimed in my former application, filed April 27, 1882, Serial No. 59,747. 40 The folding delivery mechanism herein shown is, in a broad sense, covered by claims in my former application, filed February 26, 1883, No. 86,264, and is not, therefore, so claimed 45 herein.

The specific forms of movable web-turner shown in Figs. 13 and 14 will form the subject-matter of a future application for Letters Patent.

50 What I claim is—

1. The combination, with a printing mechanism capacitated to operate upon webs of different widths, of a movable web-turner, whereby webs of different widths may be reversed without lateral transfer, substantially as described. 55

2. The combination, with a printing mechanism in which both sides of the web are printed from forms upon the same cylinder, 60 of a movable web-turner, whereby webs of different widths may be reversed without lateral transfer, substantially as described.

3. The combination, with the bars 147 148 and roll 149, mounted upon a movable frame

or carriage, as 151, of means for adjusting the 65 position of said frame, all substantially as described.

4. The combination, with a cylinder, as 129 or 130, provided with a folding-blade and a pair of co-operating folding-rolls, of sheet-carrying tapes for presenting the sheets a second time to said cylinder in proper position to receive a second fold by the same blade and rolls, all substantially as described. 70

5. The combination, with a cylinder, as 129 or 130, provided with a single folding-blade and pair of co-operating folding-rolls, of tapes, as 4 5 or 6 7, for re-presenting the sheets to said cylinder, and a switch, as 48 or 49, substantially as described. 75

6. The combination, with a cylinder, as 129 or 130, provided with a single folding-blade and pair of co-operating folding-rolls and two sets of sheet-holding devices, of tapes, as 4 5 or 6 7, for re-presenting the sheets to said cylinder, and a switch, as 48 or 49, substantially as described. 80

7. The combination, with two cylinders, as 129 130, each provided with a folding-blade and pair of co-operating folding-rolls, of means, substantially such as described, for causing said cylinders to take sheets alternately, and sheet-carrying tapes for presenting the sheets a second time to said cylinders in proper position to receive a second fold by the same blade and 90 rolls, all substantially as described. 95

8. The combination, with two cylinders, as 129 130, each provided with a single folding-blade and pair of co-operating folding-rolls, of means for causing said cylinders to take sheets alternately, tapes, as 4 5 and 6 7, for re-presenting the sheets to said cylinders, and switches, as 48 49, substantially as described. 100

9. The combination, with two cylinders, as 129 130, each provided with a single folding-blade and pair of co-operating folding-rolls and two sets of sheet-holding devices, of an oscillating guide, as 22, tapes, as 4 5 and 6 7, for re-presenting the sheets to said cylinders, and switches, as 48 49, all substantially as described. 105

10. The combination, with a single form-cylinder and a plurality of impression-cylinders and register-rolls arranged to print both sides of a web, of a web-severing mechanism and two folding-cylinders, as 129 130, each provided with two sets of sheet-holding devices; one in advance of the other, one folding-blade, and one pair of co-operating folding-rolls, substantially as described. 110 115 120

In testimony whereof I have hereunto set my hand in the presence of two subscribing witnesses.

STEPHEN D. TUCKER.
